UNITED STATES PATENT OFFICE.

MILTON E. BEST, OF LEWISBURG, PENNSYLVANIA.

SWING.

No. 900,649.

Specification of Letters Patent.

Patented Oct. 6, 1908.

Application filed June 1, 1907. Serial No. 376,843.

To all whom it may concern:

Be it known that I, MILTON E. BEST, a citizen of the United States of America, residing at Lewisburg, in the county of Union 5 and State of Pennsylvania, have invented new and useful Improvements in Swings, of which the following is a specification.

This invention relates to swings, and one of the principal objects of the same is to provide a swing which will operate by the natural movements of the body and limbs of the occupant of the swing.

Another object of the invention is to provide a swing consisting of a slatted back and 15 seat pivotally connected together, and said back and seat being pivotally connected to an arm upon each side to which the swing ropes are attached so that the natural movements of the body of the occupant of the 20 swing allow a change of position of body and will operate the swing.

Still another object of the invention is to provide a detachable foot rest which can be connected to the swing seat and arms to 25 propel the swing, and give comfort to the occupant.

These and other objects may be attained by means of the construction illustrated in the accompanying drawings, in which:

30 Figure 1 is a side elevation of a swing provided with a foot rest which may be readily connected to the swing. Fig. 2 is a detail perspective view of the manner of connecting the detachable foot rest to a swing.

35 Referring to the accompanying drawings for a more particular description of my invention, the numeral 1 designates the curved side bars of the back connected by slats 2, and 3 are the side bars of the seat pivotally 40 connected at 4 to the side bars 1 of the back, and said seat being provided with cross slats 5. The arms 6 are pivotally connected at 7 to brackets 8 securely fixed to the side bars 1 of the back by means of suitable bolts 9.

45 Pivots connected to the side bars 3 of the seat are the levers 21, said levers being pivoted upon a rod 11 extending from one side bar 3 to the other, said rod extending through said side bars and levers and being 50 threaded for the reception of nuts.

Secured to the ends of the levers 21 are spaced brackets or plates 23, and between the upper ends of the plates 23 the arms 6 are pivoted, as at 24. The swing is suspended by ropes or cables 15 which may be provided 55 with snap hooks 16 connected to screw eyes 17 secured to the arms 6. The bars 19 may be connected to the side bars 3 of the seat by a brace rod 25 which is connected to the foot rest 18 at one end and to the bars 3 at the 60 upper end and fitted with a bolt and nut 26, while the bar 21 may be connected to the foot rest 18 by means of a bracket 27, as shown in Fig. 2. The brace rod 25 serves two purposes, providing a brace for the bar 19 and 65 pivotal points for the side bars 3 and the foot rest 18.

By depressing the foot lever 18 the swing may be actuated, as will be understood, by the natural movements of the body, and add 70 comfort to the user.

From the foregoing it will be obvious that a swing made in accordance with my invention is comparatively simple in construction; is light in weight, will fold within a small 75 compass, will allow any reclining position desired, taking those positions automatically, and will actuate by the natural movements of the body of the user.

Having thus fully described the invention, 80 what is claimed as new is:—

A swing comprising a back, a seat pivoted to the back, brackets extending forward from the back, arms pivoted to said brackets, a foot rest, bars pivotally connected to the 85 foot rest upon opposite sides thereof, said bars being pivotally connected to the seat, the leg rest being pivotally connected at one end to the seat and at the other end to the foot rest, and brace rods having angularly 90 bent ends connected to the foot rest and to the seat.

In testimony whereof, I affix my signature in presence of two witnesses.

MILTON E. BEST.
